UNITED STATES PATENT OFFICE.

FREDERICK V. WINTERS, OF NEW YORK, N. Y.

VACUUM-CREATING INSTRUMENT.

Application filed February 14, 1925. Serial No. 9,279.

This invention relates to vacuum creating instruments, an object of which is to provide means of a simplified nature whereby the movable element of the vacuum creating device is assured of proper and even movement at all times during the operation and overcoming the possibility of the vacuum being prematurely destroyed or impaired.

10 The present invention has special reference to the vacuum creating instruments disclosed by my co-pending applications Serial Nos. 7431 and 8073; the present device providing means whereby the movable elements 15 in the inventions disclosed by the said applications may be more effectively actuated.

Other objects will appear hereinafter.

The invention will be described with reference to the accompanying drawings, where- 20 in preferred embodiments of the invention are disclosed.

In the drawings:

Fig. 1 is a side elevation, of one form of 25 vacuum creating device embodying the invention, a part of the gear frame being removed,

Fig. 2 is a top plan of the device shown in Fig. 1,

Fig. 3 is a sectional view taken substan- 30 tially upon line 3—3 of Fig. 1,

Fig. 4 is a similar view illustrating the invention as adapted to a different form of 35 vacuum creating implement, and

Fig. 5 is a fragmentary side elevation 35 illustrating one means which may be employed for connecting the operating element to the movable element of the vacuum creating implement.

In the application Serial No. 7431 there is 40 disclosed a vacuum creating instrument including a cylinder portion 7 within which a piston 18 reciprocates, upon downward movement of which air pressure within or beneath the covering 15 is reduced, as well 45 as within the jar J housed thereby.

In the application, Serial No. 8073 there is 45 disclosed a pair of nested cup members 4 and 5 arranged one within the other and providing between them an annular space 50 S to receive the lower end of the inverted cup member or bell 14. This lower end extends within or is submerged in a column or body of liquid, such as water, 25. In

this device, movement of the bell 14 upwardly, creates a reduction of pressure within 55 the space housed by the bell, as well as within the jar 12 confined therein.

The present invention relates to means adaptable particularly for the operation of the piston 18 of one application and bell 14 60 of the other.

In the first instance, the piston 18 is provided at its bottom with a yoke 26, the arms 27 of which are disposed, parallel with each other and extend upwardly through the exterior of the cylinder below the point of operation of the piston therein. In adapting the present invention to the device disclosed by the said application, the upwardly extending arms 27 of the yoke member are 70 provided on one edge with teeth 30, whereby the said arms, in effect, produce rack bars. These bars are in mesh with the teeth of gears 31 rotatably supported in gear framing 32 carried by the base or support of the 75 implement. One of these frames is arranged at each side of the cylinder, and each provide spaced parallel bars 33 enclosing the upstanding arms 27 at their outer ends and carrying the gears 31, intermediate gears 34 80 in mesh therewith and the main power or drive gears 35. The inner ends of these frame members are provided with bearings 36 to rotatably receive a shaft 37 to which the main power gears 35 are rigidly connected. The bearings 36 are supported upon standards 38 secured to the base of the instrument. One end of the shaft 37 is provided with an operating handle 39, by means 85 of which the shaft may be rotated. 90

In operation, the jar J is placed in proper position beneath the bell 15 while the piston 18 is in raised position. After this has been done and bell 15 is properly seated, the handle 39 is operated to rotate the gear 95 trains so as to move the rack bars 27 downwardly. This causes even downward pressure on both rack bars, whereby the piston 18 is moved bodily downward without tilting and without undue strain upon the 100 piston or any of its component parts. If desired, one or more gears of the gear train may be segments, so that rotation of the same will be limited. In such instance, the teeth will be so arranged that further operation of the gears will be prevented when 105

the yoke carrying the piston 18 has moved a prescribed distance. This will assure against undue strain upon the elastic element 19 of the piston.

5 In adapting the present invention to the instrument disclosed by application, Serial No. 8073 the dome 14 has its diametrically disposed blocks 18 provided with outwardly extending studs 17, and these studs may be either affixed to the upper ends of rack bars 40 or removably attached thereto. In Figure 4, the studs may be driven through the rack bars 40 and secured in the blocks 18, while in Figure 5 the upper ends of the 10 rack bars are recessed as at 41 to removably engage with the studs 17. In this form of the invention, the handle 39 is rotated in such direction as to cause the bell or dome 14 to move upwardly, and as the gears for 15 operation with the rack bars 40 are driven at uniform speed, the dome 14 will be moved bodily so that its lower edge throughout its circumference will travel in true horizontal position throughout its vertical movement. 20 25 From the foregoing it is apparent that means of extremely simplified nature has been provided for the accomplishment of the desired results. I am aware, however, that variations in the details of construction, the manner of associating the parts together, the means for driving the rack bars, may be subjected to variations in accomplishing the one result. I reserve to myself, therefore, the right to resort to such 30 35 variations, alterations and assemblages

without departing from the spirit of the invention as defined by the claims.

Having thus described my invention, I claim:

1. In a vacuum creating instrument, the combination with a movable member, of a pair of rack bars carried by said member at diametric points thereon, a pair of standards, gear frames comprising parallelly disposed side bars, substantially U-shaped and inclosing said rack bars at their bight portions the inner ends of said side bars having bearings, gears mounted between said side bars and operatively connected to said rack bars, and means carried by said standards and associated with the bearings of said frames for driving said gears simultaneously. 40 45 50

2. In a vacuum creating instrument, the combination with a movable member, of a pair of rack bars carried by said member, a pair of standards, gear frames associated with said standards, and comprising a bearing portion and parallelly disposed side bars, U-shaped, and inclosing said rack bars 55 60 at the bight portion of said frames, gears mounted between said side bars and operatively connected to said rack bars, a shaft supported by said standards and journaled in the bearing portion of said gear frames, and a crank fixed to said shaft for driving said gears simultaneously. 65

In testimony whereof I affix my signature.

FREDERICK V. WINTERS.
